(57) **CLAIM**

I claim the ornamental design for an electric pepper mill, as shown and described.

DESCRIPTION

FIG. 1 is a side view of the electric pepper mill showing my design, an opposite side view being a mirror image thereof.

FIG. 2 is a top plan view thereof;

FIG. 3 is a bottom view thereof;

FIG. 4 is an exploded elevation view thereof; and,

FIG. 5 is an upper perspective view thereof.
